UNITED STATES PATENT OFFICE.

FELIX KNOBLOCH, OF DETROIT, MICHIGAN.

LAUNDRY TUB.

Application filed August 29, 1924. Serial No. 734,913.

To all whom it may concern:

Be it known that I, FELIX KNOBLOCH, a citizen of the United States of America, residing at Detroit, in the county of Wayne and State of Michigan, have invented certain new and useful Improvements in Laundry Tubs, of which the following is a specification.

This invention relates to new and useful improvements in laundry tubs.

The primary object of the invention is to provide a laundry tub, formed of reinforced plastic material, with folding or collapsible supports.

A further object of the invention is to provide improved means for uniting the tub structure and its folding or collapsible supports.

Other objects and advantages of the invention will be apparent during the course of the following description.

In the accompanying drawings forming a part of this specification and in which like numerals are employed to designate like parts throughout the same,

Figure 1 illustrates a perspective view of the tub embodying this invention with its folding or collapsible supports operatively associated therewith and arranged in their set up or supporting positions,

Figure 2 illustrates in perspective the reinforcing framework of the plastic laundry tub and the folding or collapsible supports attached thereto,

Figure 3 illustrates a transverse sectional view of the structure set forth in Fig. 1,

Figure 4 illustrates a fragmentary end of the structure illustrated in Figs. 1 and 3 and shown in front elevation for illustrating the manner of connecting and bracing the supports for the tub when the latter are arranged in their set up or supporting positions,

Figure 5 is a similar view to Fig. 4 and shows the supports folded or collapsed against the bottom of the tub,

Figure 6 is a fragmentary sectional view taken upon line VI—VI of Fig. 3,

Figure 7 is a fragmentary end elevational view of one of the supports and shows the connection of permanent braces thereto, and

Figure 8 is a transverse sectional view taken upon line VIII—VIII of Fig. 7.

In the drawings, wherein for the purpose of illustration is shown a preferred embodiment of this invention, the numeral 5 des-

ignates longitudinally extending base bars which are preferably formed of angle iron of substantially inverted L-shape in cross-section. These longitudinally extending base bars are maintained in spaced relation to each other by the inverted U-shaped supports 6 which are pivotally attached to the adjacent ends of the base bars 5 by bolts and nuts 7 and are formed of suitable angular material. The depending or leg portions 8 of these supports are braced by the downwardly diverging bars 9 which are connected to the intermediate portion of the top 10 of the support and to the intermediate portions of the said legs 8. For the purpose of maintaining the supports 6 in set up or supporting positions and for permitting them to be collapsed or folded against the bottom of the tub structure, to be described at a later point, the brace bars 11 are provided and pivotally attached to the intermediate portions of the depending legs 8, as illustrated. The remaining ends of these brace bars 11 are removably attached to the base bars 5, inwardly of their ends, by bolts and nuts 12. It will now be seen that a metallic stand has been provided which possesses foldable or collapsible supports.

The base bars 5 are provided with transversely aligned openings 13 through which extend the reinforcing rods 14 which are bent into substantially U-shape and have end portions extending perpendicularly from the base bars. Extending longitudinally of the stand previously referred to are the additional reinforcing rods 15 which have their bottom portions resting upon or suitably secured to the bottom portions of the reinforcing rods 14. These reinforcing rods 15 are also of substantially U-shape, as best illustrated in Fig. 2. It will now be seen that a skeleton tub structure has been formed and permanently attached to the base bars 5 of the collapsible stand.

The plastic materials, such as cement, concrete, etc., 16 is then suitably molded around the reinforcing rods 14 and 15 so that the said rods will be embedded therein, as best illustrated in Figs. 1, 3 and 6. During the molding of this plastic material 16, a reinforcing, metallic top strip 17 is united with the plastic material 16 by means of the side walls or flanges 17^a and the laterally inwardly projecting flanges 17^b which form a part of the said strip 17. It will be seen, by inspecting Figs. 3, 4 and

5, that the upper longitudinal portion of the base bars 5 are embedded in the plastic tub material 6 so that the said base bars 5 become unitary parts of the tub.

5 In Fig. 1, there is shown a transverse partition 18 which may be suitably formed and reinforced for forming a double tub, it being understood that a tub of any desired size may be made in the manner illustrated and divided into a desirable number of compartments or sections by partitions 18.

It will now be seen that a laundry tub has been provided which is formed of reinforced plastic material and foldable or 15 collapsible supports have been secured to the tub structure in such a manner that the supports may be rigidly braced for preventing collapsing of the same during the use of the tub or they may be folded against the 20 bottom of the tub, see Fig. 5, for permitting the crating and shipping of the device. It is now believed that the manner of constructing and method of operating the laundry tub embodying this invention will be 25 completely understood from the above detail description and that no further explanation is, therefore, deemed necessary.

It is to be understood that the form of

this invention herewith shown and described is to be taken as a preferred example of the 30 same, and that various changes in the shape, size, and arrangement of parts may be resorted to without departing from the spirit of the invention or the scope of the subjoined claims.

Having thus described the invention, I claim:—

1. In a laundry tub, a tub formed of plastic material having longitudinal base bars embedded in the tub and partially projecting therefrom for mounting upon a support.

2. In a laundry tub, a tub formed of plastic material, longitudinally extending angle base bars having one flange embedded in the tub and the other flange projecting 45 therefrom for attachment to a support.

3. In a laundry tub, a tub formed of plastic material, a metallic reinforcement for the tub including longitudinal base bars of angle formation embedded therein, brace 50 rods supported by the base bars and one flange of each angle base bar extending outwardly of the tub body for attachment to a support.

In testimony whereof I affix my signature.
FELIX KNOBLOCH.
